Primary Examiner — Susan Bennett Hattan*Assistant Examiner* — Brett Miller(74) *Attorney, Agent, or Firm* — Ostrolenk Faber LLP**CLAIM**

The ornamental design for a phone charger, as shown and described.

DESCRIPTION

FIG. 1 is a front view of the phone charger of the present invention.

FIG. 2 is a perspective showing an actuated state of the phone charger of the present invention.

FIG. 3 is a top view of FIG. 2, with the bottom view being a mirror image thereof.

FIG. 4 is an elevational side view of FIG. 2, with the opposed side view being a mirror image thereof; and,

FIG. 5 is a rear view of FIG. 2.

The broken lines in the drawings depict environmental subject matter only and form no part of the claimed design.

The uneven length broken lines depict boundaries and form no part of the claimed design.

1 Claim, 2 Drawing Sheets(56)
